Primary Examiner — Nathan M Johnston(57) **CLAIM**

The ornamental design for a dispenser, as shown and described.

DESCRIPTION

FIG. 1 is a right front perspective view of a dispenser according to a first embodiment of the new design; FIG. 2 is a front elevational view thereof; FIG. 3 is a rear elevational view thereof; FIG. 4 is a right side elevational view thereof; FIG. 5 is a left side elevational view thereof; FIG. 6 is a top plan view thereof; FIG. 7 is a bottom plan view thereof; FIG. 8 is a right front perspective view of a dispenser according to a second embodiment of the new design; FIG. 9 is a front elevational view thereof; FIG. 10 is a rear elevational view thereof; FIG. 11 is a right side elevational view thereof; FIG. 12 is a left side elevational view thereof; FIG. 13 is a top plan view thereof; and, FIG. 14 is a bottom plan view thereof.

Oblique line shading shown in the drawings is included for the purpose of illustrating transparent and/or translucent surfaces. Different stippling patterns shown in the drawings are included for the purpose of illustrating different materials and/or colors that are used in the respective portions of the design.

1 Claim, 12 Drawing Sheets(56)
